PRINTING PLATE CYLINDER

Henry A. Wise Wood, New York, N. Y., assignor
to Wood Newspaper Machinery Corporation,
New York, N. Y., a corporation of Virginia

Original application May 5, 1931, Serial No.
535,165. Divided and this application June 29,
1932, Serial No. 619,887. Renewed May 4, 1937

6 Claims. (Cl. 101—378)

This is a division of my prior application Serial No. 535,165, filed May 5, 1931.

This invention relates chiefly to the printing of newspapers, or the like, in which the product is produced in a plurality of colors, but is capable of general use.

It will be obvious that where a number of cylinders are used, each having plates of a different color from the plates on the other cylinders and these are all used to form imprints on the same page, the printing plates on the different cylinders must register properly with each other. Heretofore it has been necessary, after the plates have been put on the press cylinder, to shift the plates about to obtain the proper register of the final product. This is a tedious and time-taking task and involves the printing of many proofs to see that the plates are finally in proper register.

20 My above mentioned application relates to a method and apparatus by which the plates are pre-registered and proved in a very simple manner and then easily and accurately placed on the printing cylinders in a position in which they will all register properly with each other, thus eliminating the necessity of shifting the plates after they are put on the printing cylinders and while the whole press is idle.

The principal objects of this invention are to 30 provide for the registering of printing plates by providing the plate cylinders of the printing press with fixed locating means for the plates, such as pins projecting therefrom to register the plates which have previously been proved on another machine by comparing their imprints with those of a key-plate which is placed on a cylinder and kept there in the same position, and to provide means for operating the plate clamps on the printing plate cylinder in proper relation to the 35 locating pins thereon and having means by which they can be quickly clamped and released.

Other objects and advantages of the invention will appear hereinafter.

Reference is to be had to the accompanying drawings, in which—

Fig. 1 is a radial sectional view of the printing plate cylinder of the printing press on which the proved plates are to be used, showing the manner of clamping the plates thereon;

50 Fig. 2 is a plan view, as indicated by the arrow 2 in Fig. 1;

Fig. 3 is a plan of a printing press cylinder shown in modified form, illustrating a way in which the clamps are employed when the center clip is staggered for a purpose to be described;

Fig. 4 is a sectional view on the line 4—4 of Fig. 3;

Fig. 5 is an end view of the printing plate cylinder as indicated by the arrow 5 in Fig. 3;

Fig. 6 is a view taken in the direction of the arrow 6 in Fig. 1, showing the center clip;

Fig. 7 is a side view of one of the plate locking cams used in this form of the device, and

Fig. 8 is a view of the printing plate itself with the notches therein for locating it on the printing plate cylinder.

This invention is particularly applicable to newspaper color printing and is extremely useful where more than one set of color plates is used. The principal registering means may be applied 15 to color plates that are manufactured by the electrototype process but it is designed particularly, and is especially advantageous, for stereotype plates, as each similar plate carries its characters in definite relationship to the bevels on the 20 sides of the plate and the margins on the ends of the plate. This is due to the fact that once the stereotype matrix is set in the casting-box, its relationship does not change from one plate to another.

According to this invention, the plates are pre-registered by placing a key-plate, say a black plate, in a registering machine, which is the subject of part of said application, and setting it into approximately the desired position. On this machine is an impression cylinder and a marking or notching cylinder besides the proving cylinder. The proving and marking cylinders are adapted to be inked and they are adapted also to be moved into contact with the impression cylinder which has a blanket as usual. The proving and marking cylinders are of the same size as the printing plate cylinder of the printing machine on which these plates are to be used for printing and the impression cylinder is of 40 twice that diameter.

The plates that are to be proved and registered, whether they are to be inked with black or other colored ink, are successively placed on this marking cylinder where impressions are 45 made from them and impressions made from the key-plate on the same sheet so that these impressions can be checked with respect to each other. Then the plate to be proved is adjusted on the marking cylinder until its imprint registers with the black of the key-plate on the proving cylinder. When they have been adjusted so that the registration is perfect, they are marked or notched on this marking cylinder.

In the preferred construction, notches are 55

made on these plates in their curved edges and registering pins are fixed on the press cylinder in a position so that each one of these plates that has been notched can be placed on the press cylinder with the pins in the notches. Then all 5 these plates of a series will be in exact registration with each other in the printing machine. Therefore their imprints on the web by the printing machine will be in registration and there will be no overlapping of the colors and 10 no blank spots unless such are provided for in the design. This eliminates the juggling of the plates on the printing press cylinders and transfers that part of the usual operation to this registering machine where it is done at convenient times and does not delay the locating of the plates on the printing machine.

It will be seen therefore that if it is desired to register a red plate, a trial sheet will be passed 20 under the black plate on the proving cylinder and then under the plate to be registered on the marking cylinder. The operator observes the result to see what must be done to make the red register with the black, which of course is fixed. 25 Adjustments are made for moving the red plate circumferentially or longitudinally until the proper register is obtained. Several proofs may be made before the red plate is in the proper registering position. It is at this time that the 30 red plate is notched and removed.

The plates one after another are taken off the marking or notching cylinder with the desired colored ink upon them ready to be transferred to the printing press. It will be seen that these 35 plates can be in the process of being prepared, while the printing press is running, and no time has to be taken out for the registering of the plates and only very little for placing them on the printing plate cylinders.

40 The plates may be secured on the printing plate cylinders, on which they are to be used, with their notches 19 in registration with pins 20 and 21 thereon. Of course, it will be obvious that the plates may be clamped on the printing plate 45 cylinders in any desired way and, in fact, in some of the ways that are in common use. However, I have shown in Figs. 1 and 2 one way in which the plates may be clamped, it being understood that they are registered almost instantaneously by the notches and pins.

50 In these figures a plate cylinder 54 is shown carrying an end piece 55 secured to it. In the end piece is mounted a short shaft 56 having a square 57 on the end for operating it and having a cam 58 pinned to it on the inner end. Cooperating with the cam 58 is a cam 59 pinned to a rod 60. This rod 60 passes into a chamber under the plate to be put on the cylinder and to its end is pivotally attached a pivoted arm 61. 55 The turning of the shaft 56 moves the rod 60 to the right in these figures and therefore swings this arm 61. To this arm is in turn secured a short shaft 62. This shaft also is pivotally mounted in a stationary holder 63 secured to the cylinder. The shaft 62 has secured to it a gear 64 meshing with rack teeth 65 and 66 on two operating rods 67 and 68. These operating rods 60 extend in opposite directions from the shaft 62, and their racks are arranged to engage opposite 65 sides of the gear 64. They are pivotally attached to a pair of oscillating clamp levers 69 and 70 respectively. These clamp levers are held under spring pressure against the opposite bevel edges of the plate P through a pair of operating 70 springs 71 and 72 and collars 73 on the rods 67 75 and 68.

and 68. An additional extension arm 74 is pivotally attached to one end of the arm 61 and the other end is pivotally attached to a clamp lever 75. The clamp lever 75 is held under spring pressure against the beveled edge of an inside plate P' by a mechanism similar to that described above.

It will be seen that the motion of the rod 60 to the right operates to release all of the plate-holding mechanism used on the two plates on that end of the press plate cylinder. Of course, the inner side of the plate P' is held by a center clip 76 and spring 77 and all this mechanism is repeated on the other end of the cylinder.

In this way it will be seen that the inside plate 15 may be angled underneath the center clip 76 and pressed over so that it drops down over the registering pins 21 and is thereby placed on the press in an easy manner which insures contact of the center clip and also insures a perfect 20 registration of the plate.

It will be understood, of course, that as many of these mechanisms may be employed with a set of plate clamps for each one as may be found desirable. In Fig. 4 is shown an end clamp 80 25 and center clip 81 carried by T-slots of the usual construction in the cylinder. Both are held by the pressure of springs 82 against the beveled edges of the plate. Fixed on the operating rod 83 are cams 84 arranged oppositely. When this 30 rod is rotated these cams cooperate with cam surfaces on the end clamp 80 and the center clip 81 and force these clips back in opposition to the pressure of their springs until they release the plate.

35 In Fig. 5 the rod 83 is shown as provided with a gear 85 and it is also provided with a square on its end. When this square is turned by a wrench, the gear operates two gears 86 rotatably mounted on studs 87 on the end of the cylinder. These 40 gears in turn cooperate with pinions 88 to rotate two other operating rods 89 in all respects similar to the operating rod 83.

45 In Fig. 3 the three rods are shown and the center clips 81 are arranged in staggered relationship in order to provide sufficient room for moving each center clip without providing excessive room between the clips.

The center clips 81 are shown as pressing against the inside plate while the two outer ones 50 press against the inside bevel of the outside plate. In the middle arrangement the operating cam is placed in such a way that the clip is forced to the left when the plates are unlocked.

55 Each one of these cams 84, as shown in Fig. 7, is provided with a small flat space 90 at top of the cam path so that when the clips are fully open the wrench may be taken off the square end of the central rod 83 and, on account of this flat space, there is no danger of the clips slipping into 60 closed position on account of their springs.

A circular slot 91 is provided in one of the intermediate gears 86 to cooperate with a pin 92 fixed in the cylinder to limit the motion of the whole gear train. This prevents the operating mechanism from being rotated past the proper stopping position.

65 The illustrations herein presented show the locking of only half a plate but the additional mechanism for locking the full plate with a single 70 wrench could be provided in accordance with this invention.

75 It will be seen that the machine illustrated in the original application provides means for registering the plates and proving them so that

when the plates are to be put on the printing plate cylinder of the press, the press has to be stopped only a very short time and the entire registering is accomplished outside the printing machine. Plates pre-registered and proved on the machine mentioned are almost instantaneously set on their printing plate cylinders absolutely in registering position.

Although I have illustrated and described only one form of the invention I am aware of the fact that modifications can be made therein by any person skilled in the art without departing from the scope of the invention as expressed in the claims. Therefore, I do not wish to be limited in this respect otherwise than as set forth in the claims but what I claim is:—

1. The combination with a printing plate cylinder, of oscillatable clamps for the printing plates, a rod carried by the cylinder, a shaft, said 10 rod and shaft having cooperating cam surfaces on their adjacent ends, whereby the turning of the shaft will move the rod longitudinally, and means connected to said rod for swinging said clamps into and out of clamping position according 20 to the direction in which the rod is moved.

2. The combination with a printing plate cylinder, of oscillatable clamps for the printing plates, a rod carried by the cylinder, a shaft in axial alignment with the rod, said rod and shaft 30 having cooperating cam surfaces on their adjacent ends, whereby the turning of the shaft will move the rod longitudinally, means connected to said rod for swinging said clamps into and out of clamping position according to the direction in which the rod is moved, and a series of 35 springs carried by the cylinder for moving the clamps into clamping position and for resisting the moving of the clamps into open position.

3. In a printing plate cylinder, the combination 40 of a pair of pivoted clamps for holding the opposite edges of a printing plate, a shaft carried by the plate, a rod, cam surfaces on the plate and rod cooperating to move the rod longitudi-

nally when the shaft is turned, an arm pivoted to said rod, a gear carried on a fixed axis and fixed to the arm, and a pair of rods each having a rack meshing with the said gear, each rod being connected with one of said clamps for operating it and springs on said rods for normally forcing said clamps into clamping position.

4. In a printing plate cylinder, the combination 10 of a pair of pivoted clamps for holding the opposite edges of a printing plate, a shaft carried by the plate, a rod in alignment with the shaft, cam surfaces on the plate and rod cooperating to move the rod longitudinally when the shaft is turned, an arm pivoted to said rod, a gear carried on a fixed axis and fixed to the arm whereby 15 the longitudinal motion of the rod will turn the gear, a pair of rods each having a rack meshing with the said gear located on opposite sides of the gear and extending in opposite directions therefrom, each rod being connected with one of 20 said clamps for operating it and springs on said rods for normally forcing said clamps into clamping position, a pivoted clamp for clamping the next plate on the cylinder, and means connected with one of said rods for operating the pivoted 25 clamp.

5. The combination with a printing plate cylinder, of a series of plate clamps therefor for the outside plate, center clips connected therewith for an inside plate, means for operating the 30 center clips with the clamps, said center clips being arranged alternately in staggered relationship for the purpose of providing sufficient room for moving them without leaving any excess space between the plates.

6. The combination with a printing plate cylinder, of oscillatable clamps at opposite sides of a printing plate on the cylinder, and means for simultaneously swinging said clamps toward each other to clamp the opposite edges of the 40 plate.

HENRY A. WISE WOOD.
